ABSTRACT OF THE DISCLOSURE

Filling apparatus for introducing predetermined quantities of plastisol into hollow molds in the art of slush-molding comprising a plurality of nozzles, metering cylinders containing pistons movable in one direction to induce plastisol into the cylinders and in the other direction to discharge it therefrom through the nozzles, and a plurality of gauge pins selectively positionable in the path of movement of the pistons to limit their inductive movement and hence the quantity of plastisol induced.

BACKGROUND OF THE INVENTION

This apparatus relates specifically to the filling apparatus described in my pending application Ser. No. 625,678, filed Mar. 24, 1967, and as pointed out therein one of the objects was to supply additional plastisol to the interiors of the already partially cured articles to reinforce certain areas thereof and, in particular, in the manufacture of footwear to reinforcing the heel, shank and counter areas. Since plastisol in excess of that required to coat these areas cannot be poured out without spoiling the already formed interior surface of the article, it is the purpose of this invention to limit the quantity of plastisol charged into the mold at this stage in the manufacture of the article to the exact amount required to coat the aforesaid areas so that no plastisol need be dumped out.

SUMMARY

As herein illustrated, the apparatus comprises a plurality of nozzles, means supporting the nozzles for movement to a position adjacent the open tops of hollow molds, a valve in each of the nozzles controlling the flow of plastisol through it, metering means connected to a source of plastisol and to the nozzles operable to draw in a predetermined quantity of plastisol from the source and deliver it to the nozzles, and means operable simultaneously with the delivery of the metered quantity of plastisol to the nozzles to open the valves therein. The metering means comprise pumps having intake and discharge openings, check valves associated with the intake and discharge openings operable to permit the plastisol to be drawn into the pumps and to be discharged from the pumps respectively, and means for effecting operation of the pumps. Each pump comprises cylinders containing pistons operable in one direction to induce plastisol and in the other direction to discharge plastisol, and there is means for controlling the length of the induction stroke and hence the volume of the plastisol drawn into the pump cylinder. The means for controlling the length of the stroke of the pistons in the induction stroke comprise a plurality of gauge pins, and means for moving a selected one of the gauge pins into a position to limit the induction stroke. The nozzles are supported for movement from a retracted position to a position adjacent the upper ends of the molds, there are valves in the nozzles and switch means operative by movement of the nozzles to the positions adjacent the open tops of the molds to effect opening of the valves.

2

The invention will now be described with reference to the accompanying drawings wherein:

FIG. 1 is a perspective of the filling apparatus;

FIG. 2 is an elevation, partly in section, of a support for holding a hollow mold in an upright position adjacent the discharge end of a nozzle of the filling apparatus;

FIG. 3 is a fragmentary section of a discharge nozzle, valve and valve operating means.

10 The filling apparatus herein disclosed is employed for injecting a predetermined quantity of plastisol into a hollow mold M which already has in it a partially cured layer of plastisol for the purpose of applying reinforcing layers to the inner side of the partially cured layer specifically to the counter, shank and heel pocket. The apparatus is used in conjunction with the slush-molding machine disclosed in my pending application Ser. No. 625,678, filed Mar. 24, 1967, the latter being provided with a rotor by means of which the molds are supported for movement to a position adjacent the filling apparatus. A portion of the rotor support is shown at A (FIG. 2) including clamping means B by means of which the mold is attached thereto and held in an upright position with its open top subjacent an injection nozzle.

25 There are four injection nozzles 10 supported at the upper end of a pedestal 12, the lower end of which is lagged to the floor. The nozzles are mounted for movement from a retracted position above and laterally of the supported molds at the top of the pedestal on a cap plate 14 by means of a rocker arm 16 mounted on a shaft 18 journaled in bearings 20 fixed to the cap plate for tilting movement about a horizontal axis and for movement forwardly and rearwardly with a bracket member 22 secured to the forward end of a slide plate 24, the latter resting on the rocker arm and being slidably connected thereto by bolts extending through it and through slots in the rocker arm.

30 Rocking and sliding movement of the rocker arm and slide plate are effected by power-operable means 26 and 28. The power-operable means 26 comprises a cylinder 30 pivotally connected by a pin 32 to the pedestal and a rod 34 extending from the cylinder and pivotally connected at its distal end by a pin 36 to the forward end of the rocker arm. The power-operable means 28 is a cylinder 38 pivotally connected by a pin 40 to the rear end of the rocker arm and a rod 42 extending therefrom and connected at its distal end by a pin 44 to the slide plate 24. The power-operable means are double-acting so that pressure supplied to the lower end of the cylinder 26, as shown, will extend the rod 34 and hence raise the rocker arm and pressure supplied to the upper end will retract the rod and hence lower the rocker arm. Pressure supplied to the rear end of the cylinder 38 will extend the rod 42 and thus advance the slide plate forwardly on the rocker arm and pressure supplied to the forward end of the cylinder 38 will retract the rod and hence move the slide plate rearwardly on the rocker arm. Pressure is supplied to the cylinders 26 and 38 simultaneously so as to effect movement of the slide plate forwardly and the rocker arm downwardly to move the nozzles 10 from their retracted position to a position above the open ends of the molds.

35 Plastisol is supplied to the nozzles 10 in predetermined quantities by metering means 46 comprising tandemly arranged chambers 46a and 46b containing pistons (not shown). The piston in the chamber 46a is connected to the piston in the chamber 46b and is movable by the latter downwardly in the chamber 46a to induct plastisol and upwardly in the chamber 46a to discharge it. There are 40 two metering means 46, one mounted at each side of the pedestal on a plate 48 extending downwardly from the

cap plate 14 and each is connected to a source of plastisol for supplying a predetermined quantity of plastisol to two of the nozzles 10. A single conductor 50 supplies plastisol from the source through a coupling 52 to the upper end of the chamber 46a and the coupling contains a check valve which admits plastisol through it to the chamber when the piston therein is moving downwardly and checks it when the piston is moving upwardly. The upper end of each chamber 46a is connected by a double coupling 54 and two conductors 56 to two of the nozzle 10. The double coupling contains a check valve which permits the plastisol to flow from the chamber 46a through the conductors 56 upon discharge, that is, upward movement of the piston in the chamber 46a and prevents retraction of plastisol in the conductors 56 on the downward stroke of the piston in the chamber 46a.

The quantity of plastisol drawn into the chamber 46a is controlled and may be set to the desired amount by means of gauge pins 56 which are supported at the lower end of the metering means on a circular plate 58. The plate 58 is fixed to the upper end of a shaft 60, journaled in a frame 62, in spaced parallel relation to the axis of a piston rod 64 extending through the lower end of the chamber 46b from the piston therein. The gauge pins 56 are disposed in a circle about the axis of the shaft 60, the radius of which corresponds to the distance between the axis of the shaft 60 and the axis of the piston rod 64 so that by rotating the plate the pins may be moved to a position directly below the lower end of the piston rod 64. The pins are graduated in length from the shortest which is shown at the right side of the piston rod to the longest which is shown at the left-hand side to provide for limiting the movement of the piston in the chamber 46b and hence the quantity of plastisol that may be drawn into the chamber 46a. There is a space between the shortest and the longest so that the piston rod may be moved to its extreme position and thereby fill the entire chamber 46a. The shaft 60 has on its lower end within the bracket member 62 a sprocket (not shown) about which one end of a chain 66 is entrained, the opposite end of the chain being entrained about sprocket 68 secured to the shaft 70 of a motor 72. There is also on the shaft a disc carrying a plurality of contacts corresponding in number to the pins so that it is possible by programming to start the motor to effect rotation of the plate 58 and to stop it with a specific pin beneath the lower end of the piston rod 64 by grounding the contact representing that pin.

Discharge of a predetermined quantity of plastisol as determined by the gauging pin selected is effected by opening valves in the nozzles 10 substantially simultaneously with the movement of the nozzles forwardly and downwardly into positions above the open ends of the molds. Each nozzle contains a ball valve 74 (FIG. 3) in which there is a diametrical hole 76 and has fixed to it a stem 78 by means of which the ball valve may be rotated to dispose the hole across the nozzle or in alignment with the passage 80 therethrough. The stem extend rearwardly from the nozzles and are connected to forwardly extending shafts 82 journaled in the lower ends of a plurality of cylinders 84 which contain pistons and from the lower end of which extends piston rods 86. Each rod has on it a rack 88 and each shaft has on it a gear 89 meshing with the rack so that movement of the piston downwardly in the cylinder through the rack, gear and shaft effects rotation of the spindle and hence the valve in the nozzle to a position for discharge and movement in the piston in the opposite direction effects rotation of the valve in a direction to close the passage through the nozzle.

Pressure for moving the pistons downwardly is supplied to the upper ends of the cylinders through conductors 90 and to the lower ends through conductors 92. The conductors 90 and 92 are connected to a valve 94 to which pressure is supplied through a conductor 96. The valves

94 are solenoid-operated in one position to connect the conductors 90 with the conductor 96 and in the other position to connect the conductors 92 with the conductor 96. The solenoids are electrically activated by a switch 98 mounted on the pedestal 12 beneath the rocker arm 16 in a position to be engaged by an adjustable screw 100 mounted on the underside of the rocker arm, the adjustment of which will determine when the switch 98 is activated.

As pointed out above, the metering means 46 are independently operable so that it is possible to supply different quantities of plastisol, for example, a large quantity to one pair of nozzles 10 for large boots and a smaller quantity of plastisol to the other pair of nozzles 10 for smaller boots. If different quantities of plastisol are discharged from the two pairs of nozzles, it is apparent that discharge through the pair to which the smaller quantity of plastisol is supplied will be completed before discharge through the other pair. Since the valves, as related above, are not closed until the rocker arm 16 is elevated, the nozzles through which the smaller quantity of plastisol has been injected, remain open, while plastisol continues to be discharged from the other nozzles and may drip due to draining of the plastisol clinging to the interior of the conductors 56, or to a check valve which does not seat tightly enough so that plastisol escapes around it into the conductors 56. To remedy and prevent such possible drip in the event of a faulty check valve, a limit switch LS is provided for each metering device which is operable, when the piston in the chamber 46a reaches the end of its discharge stroke, to effect closing of the valves in the nozzles associated with the metering means even though the rocker arm 16 is still in its depressed position and hence still engaged with the switch 98. As herein illustrated, a switch LS is mounted on each bracket plate 61 adjacent the piston rod 64 and a part 63 is mounted on the piston rod so that it actuates the switch LS when it reaches the upper end of its stroke which corresponds to the completion of the discharge stroke of the piston in the chamber 46a.

In normal operation of the apparatus a programming switch is selected which corresponds to the amount of plastisol desired and is activated to rotate the correct gauging pin into position beneath the lower end of the piston rod 64. Following this pressure is supplied to the upper end of the chamber 46b to drive the piston downwardly therein against the pin which at the same time by lowering the piston in the chamber 46a induces the desired amount of plastisol. The pressure is now reversed in the chamber 46b to drive the latter upwardly and correspondingly the piston in the chamber 46a to effect discharge of the plastisol from the chamber to the nozzles and simultaneously the slide plate and rocker arm move forwardly and downwardly to bring the nozzles into a position above the upper ends of the molds and to activate the switch 98 so as to open the valves. Air is again supplied to the upper end of the cylinders 26 and 28 to move the nozzles to their inoperative position.

I claim:

1. Injection apparatus for delivering a measured quantity of plastisol into the open top of a hollow mold comprising a nozzle containing a valve, first means connected to the valve for opening it, metering means connected to a source of plastisol and to the nozzle operable to induct a predetermined quantity of plastisol from the source, said metering means being further operable to inject said inducted quantity of plastisol into the nozzle, second means for effecting operation of the metering means to inject said inducted quantity of plastisol into the nozzle, means supporting the nozzle for movement from a retracted position to a position adjacent the open top of the mold, said means embodying a rocker arm supported for tilting movement about a horizontal axis and a slide plate mounted on the rocker arm for movement forwardly and rearwardly on the arm toward and from

the mold, third means for effecting movement of the rocker arm and slide to present the nozzle to the open top of the mold, and means operable to effect substantially simultaneous operation of said first, second and third means.

2. Injection apparatus according to claim 1, wherein said metering means comprises a pump having intake and discharge openings, check valves associated with the intake and discharge openings operable to permit plastisol to be drawn into the pump and to be discharged from the pump respectively, and means for effecting operation of the pump.

3. Injection apparatus according to claim 1, wherein said metering means comprises a pump cylinder having intake and discharge openings, a piston in the cylinder, intake and discharge valves connecting the cylinder respectively to the source of plastisol and to the nozzle, means for effecting reciprocation of the piston to induce the plastisol through the intake valve on one stroke and discharge it from the cylinder through the discharge valve on the reverse stroke, and means for controlling the length of the induction stroke and hence the volume of plastisol drawn into the pump cylinder.

4. Injection apparatus according to claim 1, wherein said metering means comprises a pump cylinder containing a piston operable, by movement in one direction, to draw plastisol from the source into the cylinder and in the opposite direction to discharge plastisol from the cylinder, means for controlling the length of the stroke of the piston in the one direction comprising a plurality of gauge pins, and means for moving a selected one of said gauge pins into a position to limit the stroke of the piston in said one direction.

5. Injection apparatus according to claim 1, wherein said last means is electrically operable, comprising a switch for effecting operation of said electrically operable means, and means on the rocker arm operable, by downward movement of the rocker arm to a position such that the nozzle is adjacent the open top of the mold, to actuate the switch and by elevation of the rocker arm to de-active the switch.

6. Injection apparatus according to claim 5, wherein said means on the rocker arm is a screw mounted thereon and adjustable relative thereto.

7. Injection apparatus comprising a support, a plurality of nozzles mounted on the support for movement from retracted positions above and laterally of the open tops of a plurality of hollow molds supported in upright positions to positions adjacent the open tops thereof, two metering means, a single conductor connecting each metering means to said source of plastisol, two conductors connecting each metering means to each nozzle of a pair of nozzles for supplying a predetermined quantity of plastisol to each nozzle, valves in the nozzles, power-operable means for effecting movement of the nozzles from said retracted positions to said positions at the open tops of the molds, and means operable when the nozzles reach said positions adjacent the open tops of the molds to open said valves.

8. Injection apparatus comprising a support, a plurality of nozzles mounted on the support for movement from retracted positions above and laterally of the open tops of a plurality of hollow molds supported in upright positions to positions adjacent the open tops thereof, a source of plastisol, metering means for supplying plastisol to said nozzles and discharging it therefrom, means connecting certain of the nozzles to one metering means and others of the nozzles to other metering means, means operable to control said metering means independently

to enable supplying different quantities of plastisol to the different nozzles, valves in the nozzles, switch means operable by movement of the nozzles away from the open tops of the molds to close the valves, and means operable before the nozzles are moved away from the open tops of the molds in the event that one of said metering means has completed its discharge before another to cause said last-named means to close the valves in the nozzles associated therewith.

9. Injection apparatus comprising a support, a plurality of nozzles mounted on the support for movement from retracted positions above and laterally of the open tops of a plurality of hollow molds supported in upright positions to positions adjacent the open tops thereof, a source of plastisol, plural metering means for supplying plastisol to said nozzles and discharging it therefrom, means connecting certain of the nozzles to one metering means and others of the nozzles to other metering means, means operable to control said metering means independently to enable supplying different quantities of plastisol to the different nozzles, valves in the nozzles, first switch means operable by movement of the nozzles to said positions adjacent the open tops of the molds to open said valves, said switch means being further operable by movement of the nozzles away from the open tops of the mold to close said valves, and second switch means operable independently of said first switch means to close said valves, and means movable by each metering means at the end of its discharge stroke to actuate said second switch means.

10. Injection apparatus comprising a combination rocker and slide plate supporting the nozzles for movement from a lateral elevated position to a position above the open tops of the molds, a plurality of metering means, means connecting certain of the nozzles to one metering means and other nozzles to another metering means, means operable to effect independent control of the metering means to enable supplying different quantities of plastisol to the different molds, valves in the nozzles, first switch means operable by the rocker as it lowers the nozzles into a position above the open tops of the molds, said first switch means being operable when the rocker is elevated to close the valves, second switch means, one associated with each metering means, independently operable to close the valves at the termination of the discharge stroke of the metering means with which they are associated, said metering means each embodying a cylinder containing a piston rod, gauge pins which control the stroke by limiting movement of the piston rod, and a part on the piston rod movable into contact with the second switch means when the metering means reaches the end of its discharge stroke to close the valves of the nozzles associated therewith.
